UNITED STATES PATENT OFFICE.

GEORGE H. CLARK, OF CRESCENT CITY, ILLINOIS.

DESIGN FOR A THILL-IRON.

SPECIFICATION forming part of Design No. 32,826, dated June 12, 1900.

Application filed May 8, 1900. Serial No. 15,982. Term of patent 7 years.

To all whom it may concern:

Be it known that I, GEORGE H. CLARK, a citizen of the United States, residing at Crescent City, in the county of Iroquois and State of Illinois, have invented and produced a new and original Design for Thill-Irons; and I do hereby declare the following to be a full, clear, and exact description of the invention, such as will enable others skilled in the art to which it appertains to make and use the same.

In the drawings, Figure 1 is a side view of the thill-iron. Fig. 2 is a plan view of the same.

As shown in the drawings, the leading or material feature of the design consists of the Y-shaped bracket *b*, which projects laterally from one side of the main portion *c* of the thill-iron near its front end and in the same plane as the said main portion. The rear portion of the thill-iron is curved downwardly at *d* and has an eye *e* for attachment to the ve-

hicle. Holes *f* are provided in the thill-iron for attaching it to the shafts or thills of the vehicle. The tops of the arms of the Y-shaped bracket join onto the main portion of the thill-iron, the space between the arms being left open, and the stem of the bracket, which is secured to the cross-piece between the thills, projects from the apex of the triangle of which the arms form two sides and is arranged at an angle with the main portion *c* to suit the convergence of the thills.

What I claim is—

The design for a thill-iron, as herein shown and described.

In testimony whereof I affix my signature in presence of two witnesses.

GEORGE H. CLARK.

Witnesses:

C. C. PARKMAN,
L. H. CARSON.
